BOTTLE CRATE

John A. Hopwood, Great Neck, N. Y.

Application March 11, 1935, Serial No. 10,362

2 Claims. (Cl. 217—65)

This invention is a bottle crate intended more particularly for the retail distribution of milk, and the invention is directed primarily to a crate, so constructed that a plurality of such crates may be readily stacked in superimposed relation and in a manner to maintain vertical alignment of the walls of the crates so stacked.

Stacking devices on bottle crates have long been used and the present invention is directed to certain improvements in the crate construction, wherein the stacking device may be economically manufactured and associated with the crate in the course of manufacture of the latter. To this end, the so-called stacking iron is, according to the present invention, formed independently of the corner irons of the crate and is adapted to be attached thereto and to the crate mainly by the means which holds the crate in assembled relation, said means serving further to attach to the crate a metallic runner, which will provide a flat surface while adapted to cooperate with stacking irons of another crate of the same kind, when a plurality of such crates are stacked in order that wear may be minimized and a firm stack produced and one which will not be apt to wobble or fall over.

With these objects in mind, the present invention consists in novel details of construction, more specifically set forth in the following detailed description, shown in the accompanying drawings and set forth in the appended claims.

The accompanying drawings illustrate different practical embodiments of the invention, but the constructions therein shown are to be understood as illustrative, only, and not as defining the limits of the invention.

Figure 1 is a fragmental perspective of one corner of a crate embodying the present invention, showing a portion of the upper edge of the crate and similar parts of two of the vertical walls thereof.

Figure 2 is a view similar to Figure 1, but showing the parts of the crate construction partially dismantled in order that their individual structures may be more clearly illustrated.

Figure 3 is a plan view of one of the stacking irons with an associated cover cap to which the stacking iron is attached.

Figure 4 is a section on the line 4—4 of Figure 3.

Figure 5 is an edge view of the assembly shown in Figure 3 looking from the right hand side of the latter figure.

Figure 6 is a view similar to Figure 4, but illustrating a modified form of construction.

Figure 7 is a fragmental perspective view showing the lower portion of the crate and looking up from the bottom thereof with the metallic parts of the structure partially dismantled to more clearly disclose their structures.

The crate of the present invention embodies four walls arranged in rectangular relation. These walls may be solid, if desired, but are shown as embodying a plurality of slats 1, arranged in superimposed relation, so that the crate embodies in effect a plurality of slat frames arranged in superimposed relation to form the four sides of the crate.

At each of the four corners of the crate is provided a corner iron 2, the opposite ends of which are provided with upper tongues 3 and lower tongues 4 arranged in right angular relation to one another to overlie the upper and lower edges of the crate, as shown best in Figures 2 and 7. The upper edges of the crate are provided with recesses 5 to receive the tongues 3, while the lower edges of the crate are recessed at 6 to receive the lower tongues 4. The recesses 6 are made deep enough, so that, when the tongues 4 occupy them, the lower faces of the tongues are flush with the remainder of the bottom edges of the crate, while the recesses 5 are made somewhat deeper, so as to not only receive the tongues 3, but also to receive corner caps 7, so that the upper faces of the latter are flush with the upper edges of the crate walls. Each of the corner caps 7 is in the form of a substantially flat plate provided at its inner and outer margins with depending flanges 8, which are adapted to extend down over the interior and exterior surfaces of the walls of the crate for a distance to protect the ends of the slats against splitting and the outer flanges are offset, as shown at 9, so as to provide for the thickness of the corner irons and insure that the flanges 8 will closely hug the corner irons and the surfaces of the crate walls to form a tight fit therewith.

The stacking irons are made separate from the corner caps 7 and are in the form of stamped or pressed sheet metal of relatively heavy gauge to give sufficient strength. Each stacking iron comprises a flat, right angular plate 10 at the inner angle of which is formed an upstanding hollow boss 11 having outer inclined sides 12 and a substantially flat top 13 which merges into the inclined sides 12 with sweeping curves 14, so as to eliminate all angles which might catch when stacking crates in superimposed relation. The flat top portion 13 is amply supported on two of its sides by the inclined por-

tions 12, which cooperate with one another in supporting the flat top when shocks are received by the latter, and said inclined sides 12 also diverge from the flat top in the direction of 5 the plate 10, so as to give maximum strength in the structure to preclude bending or deformation under hard usage.

The free edge of the flat top 13 is preferably curved out slightly, as shown at 15, so as to give 10 the flat top a somewhat larger area than would otherwise be the case and thus protect wooden parts of other crates from damage when brought in contact therewith. All of the edges of the stacking iron are preferably rounded, so as to 15 give no sharp edges.

Each stacking iron is adapted to rest on the upper surface of one of the corner caps 7 and to be secured thereto and to the crate primarily by the means which holds the other parts of the 20 crate in assembled relation. To this end, the plate 10 of each stacking iron is provided with countersunk holes 16 adapted to cooperate and aline with similarly formed holes 17 in the corner cap and the holes in these two parts are so positioned as to register or aline with holes 13 in the upper tongues 3 of the corner irons 2 and holes 19 in the several superimposed bars 1 of the walls of the crate, so that tie rods 20 may be passed successively through the stacking irons, 25 corner caps 7, tongues 3 and the several slats 1 to secure the corner irons, corner caps and stacking irons to one another and to the slats of the crate in order that the said parts of the crate may be held in assembled relation by the tie rods 30 20. The upper ends of the tie rods are headed, as shown at 21, and these heads are received in the countersunk holes 16 to give a substantially flush upper surface to the plate 10.

Tie rods 20, after passing downwardly through 40 said several parts described, and as shown in Figure 2, are adapted to pass through holes 22 in the lower tongues 4 of the corner irons and thence through holes 23 in a metallic runner 24, as shown in Figure 7, said latter holes 23 being 45 countersunk to give a flush lower surface to the runner and the rods 20 being headed within said countersunk holes.

The runner 24 is constructed from sheet metal and comprises a bottom plate 25, all parts of 50 which occupy the same horizontal plane, so as to give a perfectly flat bottom and at the lateral edges of this flat plate 25 are upstanding flanges 26 which extend upwardly over the inner and outer surfaces of the bottom slats and over the 55 corresponding edges of the lower tongues 4, so as to completely enclose and conceal such lower edges and the tongues and to also enclose and conceal the lower recesses 6 in which said tongues are received.

The plate 25 is of a length to extend along 60 the complete length of the side wall with which it is associated and is turned at the adjacent corners of the crate and extends for a distance along the two adjacent side walls, so that said 65 plate may be said to be U-shaped. As stated, it is provided with the flanges 26 along its entire extent, so that said flanges conceal the edges, tongues and recesses, as stated, and at the same time reinforce the edges of the crate in such 70 manner as to preclude splitting or splintering thereof. Said flanges are, as shown, offset slightly at 27 to provide for the extra thickness of the corner angles and to permit said flanges 26 to closely hug the corner irons and the slats, and, 75 if desired, the runner 24 may have a forced fit

with these parts or may be pressed firmly against said parts, so as to thereby form an anchorage which will preclude rattling and help to hold the runners in place.

It will be understood, however, that the walls 5 of the crate and all of the metal parts which I have described, are held in assembled relation by the tie rods 20, which are threaded through the parts in succession and headed over while the parts are held under compression in order to produce a tight construction with the rods 20 under more or less tension, so that rattling of the parts will be precluded. It should be noted in this connection that each of the corner irons is provided with external shouldered bosses 28, so positioned 10 that, when the tie rods are headed over, the edges of the flanges 26 and 8 will be drawn tightly to a seat on these bosses. This serves two purposes, first, it helps to take up the tension of the tie rods, and, secondly, these bosses serve as 15 camming surfaces, so that if the corner of the crate is moved vertically while in engagement with some extraneous objects, the boss will fend off the crate or object, so that the free edges of the flanges 8 will not be caught and deformed. 20

By providing a flat bottom or plane surface runner as described, this runner will rest flat on the plate 10 of the stacking iron, when crates are stacked and will form a proper seat therewith, so as to give a firm stack which will not 25 tilt or fall over. At the same time, the flanges 26 on the inner edges of the runner form at the corner a firm metal angle to cooperate with the raised extension of the stacker to be guided thereby as the crates are stacked into true vertical alignment without undue wear on the parts and without contact between the metal parts and the wooden parts of the crate during the stacking operation. 30

As the tie rods 20 are spaced some little distance from the corner in order to properly secure the slats together without splitting, there may be some tendency under the most hard usage for the stacking irons to lift slightly at their outer corners and for this reason, I preferably permanently anchor them down in this region. This may be accomplished by the use of a rivet 29 passed through perforations 30 and 31 in the stacking iron and corner cap and headed over and properly countersunk, so that the parts are 45 anchored together in the region stated. In lieu of rivet 29, I may, however, punch out a projection 32 from either the stock of the corner cap or the stacking iron and then perforate the other part, so that the projection 32 may extend 50 through the perforation and then be crushed or headed, as shown in Figure 6, to provide integral anchorage means. I do not consider this anchorage as an absolute essential, but it is preferably 55 employed for the reasons stated. 60

It will be understood that the runner 24 may extend along either the longer sides or the shorter sides of the crate, as may be desired, the invention not being restricted in this connection.

I have not attempted to show in the accompanying drawings, the interior of the crate construction, as this may consist in any approved means for dividing the interior of the crate into individual compartments for the bottles to properly support the bottles in said compartments. 65

The foregoing detailed description sets forth the invention in its preferred practical form, but the invention is to be understood as fully commensurate with the appended claims. 70

Having thus fully described the invention, what I claim as new and desire to secure by Letters Patent is:

1. A bottle crate comprising four walls, each consisting of superimposed slats, corner irons at the four corners of the crate provided adjacent the upper and lower edges of the crate with external shouldered bosses, corner caps overlying the upper four corners of the crate and provided with depending flanges at their inner and outer edges to overlap the inner and outer faces of the uppermost slats and seat upon the upper shouldered bosses of the corner irons, runners extending along the lower edges of two opposite walls of the crate for the full length thereof and for a portion of the length of the other two opposite walls of the crate and having at the inner and outer edges of said runners upstanding flanges overlying the inner and outer faces of the lowermost slats of the crate and seating against the lower shouldered bosses of the corner irons,
- 5 and tie rods extending vertically through the slats and through the caps and runners to secure the caps and runners together and to the interposed slats.
2. A bottle crate comprising four walls, corner irons at the four corners of the crate provided adjacent the upper and lower edges of the crate with external shouldered bosses, top metal plates overlying the upper four corners of the crate and provided with depending flanges seated on the 10 upper shouldered bosses of the corner irons, bottom metal plates underlying the bottom four corners of the crate and provided with upstanding flanges seated on the lower shoulder bosses of the corner irons, and tie rods extending vertically through the walls of the crate and anchored with respect to said top and bottom plates to secure the respective top and bottom plates to one another and to the interposed walls.
